UNITED STATES PATENT OFFICE.

FRANK SZ. BUDAJI, OF NEW YORK, N. Y.

LATCH FOR DOORS.

1,294,612.

Specification of Letters Patent.

Patented Feb. 18, 1919.

Application filed May 16, 1918. Serial No. 234,985.

To all whom it may concern:

Be it known that I, FRANK SZ. BUDAJI, a subject of the King of Hungary, (having declared his intention to become a citizen of the United States of America,) residing at New York, in the county of New York and State of New York, have invented certain new and useful Improvements in Latches for Doors, of which the following is a specification.

My invention relates to improvements in sliding latches for doors, or the like, and is of such construction as to render it operable only when the knobs are turned.

15 A further object of the invention is the provision of a sliding latch of that construction which requires the turning of the knob to release the latch from its housing in the door frame.

20 A still further object is the provision of a sliding latch of this character, which shall be simple, practical and comparatively inexpensive in construction and one that can be manufactured and sold at a low cost.

25 With these and other objects in view, the invention consists of the novel combination and arrangement of parts hereinafter more fully described and set forth in the claims hereto appended.

30 In the drawings,

Figure 1 is a vertical sectional view of my improved latch in operative position, the part of the door in side elevation;

Fig. 2 is a horizontal sectional view;

Fig. 3 is a view similar to one illustrating the latch in retracted or inoperative position;

Fig. 4 is a perspective view of the latch and rack bar;

Fig. 5 is a perspective view of the releasing bar;

Fig. 6 is a perspective view of the latch retaining member; and

Fig. 7 is a fragmentary perspective view of the keeper bar.

Referring to the drawings, the numeral 5 designates a fragmentary portion of a door frame having formed therein the usual latch housing 6 and bolt housing 7, the front walls of these housings being protected by the usual guard plate 8 secured thereto by any suitable fastening means 9, such as screws or the like.

10 The door is designated by the numeral 10 and is provided with a suitable recess 11 in which my improved slidable latch is

mounted. The front wall of the recess 11 is closed by a plate 12 which is secured thereto by fastening means 13. This plate constitutes a support for the latch when mounted therein.

Arranged within the recess 11 adjacent the rear wall is a drum 14 and the ends of this drum are journaled on the opposite side wall of the recess, as illustrated in Fig. 2. 65 A knob shaft 15 is secured in the drum 14 and the ends of this shaft project laterally beyond the outer faces of the side walls of the recess and have secured thereto the operating knobs 16.

70 A pin or shaft 17 is secured to the opposing faces of the side walls of the recess and adjacent the drum 14 and this pin has pivoted thereon a locking bar 18, the rear end of which is provided in its under side with an 75 inverted V-shaped notch 19, the rear wall of which is beveled as at 20. The notch 19 of the bar 18 is adapted to receive the beveled lug 21 formed on the drum 14 and this lug tends to hold the latch 22 in operative or 80 locked position. By virtue of the shaft 17 being located near the center of the bar 18, the said bar will be normally disposed in a horizontal position and the latch 22 in locked position.

85 The latch 22 has the usual beveled face 23 and is adapted to be slid into and out of the recess 6 and the door frame 5. This latch is slidable in the housing 24 formed on the plate 8.

90 A second shaft 25 is journaled in the opposing side walls of the recess 11 forwardly of the shaft or rod 17 and this shaft 25 has secured thereon a gear wheel 26 which meshes with the teeth 27 of the rack bar 28, 95 the forward end of this rack bar being pivotally secured as at 29 to the lugs 30 carried by the rear face of the latch 22. The forward portion of the rack bar is slidable through a guide 31 extending vertically 100 from the bottom wall of the housing 24.

A coiled spring 32 surrounds the portion of the rack bar forwardly of the guide 31 and when the latch is retracted this spring is placed under compression whereby 105 upon the release of the pressure on the knob 16 the latch will be returned to its extended position.

110 A sprocket chain 33 has one end secured as at 34 to the drum 14 and its free end is trained over and secured to a sprocket wheel 35 carried by the second shaft 25. A pair of

spaced teeth 36 are arranged on opposite sides of the chain 33 and carried by the drum so that upon the turning of the drum the teeth 36 will engage the links of the chain 33 causing a rotation of the shaft 25 which in turn rotates the gear 26 which is normally in mesh with the teeth of the rack bar 28, thus moving the rack bar rearwardly and retracting the latch 22 from its housing 6 60 10 against the tension of the spring 32.

A latch retaining member 37 is pivoted intermediate its ends on a vertical pin 38. The forward end of this retaining member is reduced and bent angularly to provide a 15 keeper 39 which is adapted to be moved into and out of the vertical recess 40 in the side face of the latch 22. The rear end of this retaining member 37 is bent in a direction opposite to the direction of the keeper 39 and 20 it is provided with a diagonal opening 41 which is adapted to receive a headed end 42 of the rod 43 which has its free end secured as at 44 to the forward end of the locking bar 18.

25 It will be understood that when the latch is in the extended position the keeper 39 of the retaining member is within the recess 40 of the latch and the headed end 42 of the rod 43 abuts the upper wall of the slot 41. 30 When the parts are in this position, the lug 21 of the drum is in the recess 19 of the bar and a chain 33 is partially wound about its sprocket wheel 35. Immediately upon the turning of the shaft 15 by pressure on the 35 knob 16, the lug 21 due to its inclined face riding over the inclined wall 20 of the recess 19 will urge the rear end of the bar 18 upwardly moving the headed end of the rod 43 downwardly in the slot 41, thus swinging 40 the retaining member on its pivot pin 38 and releasing the keeper 39 from the recess in the latch. By further turning movement of the shaft 15, the latch will be retracted by virtue of the chain 33 winding upon the 45 drum 14 and the gear 26 retracting the rack bar, thus moving the latch free of its housing 6 and compressing the spring 32. Immediately upon the release of pressure on the knobs the spring 32 will act to cause the 50 latch to seat its extended position.

To lock the shaft 15 against rotation, the drum is provided with a pin 44 which is adapted to enter the openings 45 formed in the horizontally disposed rod 46. This rod 55 is located in the recess and is pivoted intermediate its ends with a lug 47 so that it may

be readily locked into pin engaging position as illustrated in Fig. 1 in dotted lines. A bell crank lever 48 has one end pivotally secured as at 49 to the forward end of the 60 rod 46 and the free end of this lever is pivotally secured as at 50 to the operating member 51, which member is located exteriorly of the plate 8 so that access may be readily had for its operation. 65

Having thus described my invention, what I claim is:—

1. In combination, a door having a recess opening out through one wall thereof a latch mechanism located within said recess 70 and comprising a knob shaft, a drum journaled in the side wall of the recess and secured to the shaft, a locking bar pivoted to the side wall of the recess above said drum, a latch slideable in the recess of the door, a 75 rack bar carried by the latch, means located within the recess and connected to the drum and rack bar whereby upon turning of the drum the latch may be retracted or extended, spring means associated with the rack 80 bar and latch for automatically retaining the latch to extended position, and a retaining means operated by the lock bar for engagement with the latch to hold the same extended until the drum is rotated, and a locking means to hold said drum against rotation. 85

2. A sliding latch including a housing, a knob shaft carrying a drum journaled in said housing, a latch member slideable 90 through one wall of said housing forwardly of said drum, a shaft journaled in said housing, a lock bar pivoted to said shaft, a second shaft journaled in said housing forwardly of the first named shaft, a gear on 95 the second shaft, a rack bar pivoted to the rear of said latch member and meshing at its opposite end with the gear of the second shaft, a retaining member pivoted in said housing, a keeper formed on one end of said 100 retaining member and engaging said latch to hold the latter extended, a rod connected to said retaining member and locking bar, means connecting the drum to the second shaft whereby upon turning of the knob 105 shaft said retaining member may be released from the latch member and permit the latch member to be retracted, and spring means for returning said latch member to its extended position. 110

In testimony whereof I affix my signature.
FRANK SZ. BUDAJI.
